UNITED STATES PATENT OFFICE.

CUTHBERT B. LOWRY, OF LEXINGTON, KENTUCKY, AND RICHARD BERNHARD, OF CHICAGO,
ILLINOIS.

MEANS FOR WITHDRAWING AND CONDENSING VAPORS.

No. 902,097.

Specification of Letters Patent.

Patented Oct. 27, 1908.

Application filed May 9, 1906. Serial No. 316,023.

To all whom it may concern:

Be it known that we, CUTHBERT B. LOWRY, of Lexington, in the county of Fayette, State of Kentucky, and RICHARD BERNHARD, of Chicago, in the county of Cook and State of Illinois, have invented certain new and useful Improvements in Means for Withdrawing and Condensing Vapors; and we do hereby declare the following to be a full, clear, and exact description of the invention, such as will enable others skilled in the art to which it appertains to make and use the same.

The primary object of this invention is to provide a condenser wherein the condensation of steam or vapor gases is gradually or progressively accomplished and the heat given off by the gases is utilized to increase the velocity of the cooling water and thereby prevent the escape of the non-condensable globules of gas, the combined volume of which is greatly reduced.

As is well known in the art, the production of a vacuum within a wood impregnating apparatus requires the withdrawal of the vapors of creosoting oils, or like compounds, and heretofore this has necessitated the use of a pump in connection with a condenser, regardless of whether or not the vapors themselves were to be condensed.

Our present invention is particularly applicable to this class of work.

The invention will be hereinafter fully set forth and particularly pointed out in the claim.

In the accompanying drawings, Figure 1 is an elevation showing the application of our improvement to a wood impregnating apparatus, the latter being conventionally indicated. Fig. 2 is a vertical longitudinal section of the condenser.

Referring to the drawings, 1 designates a wood impregnating apparatus, which may be of any suitable form of construction, from the dome 2 of which leads a valved pipe 3 through which the gases or vapors are designed to pass. This pipe is extended upwardly some distance, and through a horizontal connection opens into the upper end 50 of a condenser 4. The lower or outlet end of this condenser is connected by a pipe or tube 5 to a well 6 located at a point considerably below the wood impregnating apparatus. The length of the pipes, or the point at which

the condenser itself must be located, is dependent upon the height of the column of water in pipe 5, as the weight of this column of water must balance the atmosphere, because pipe 5 acts as a barometric tube, thereby withdrawing the gases or vapors from the apparatus into and downwardly through the condenser. In order to enable the condenser to perform this operation, and to successfully remove the air rapidly, it is necessary that the action of the condensing water on the vapors and gases be cumulative as well as multiple. The intermingling of the water with the gases is so efficiently accomplished in this condenser, the action being repeated a number of times, that the non-condensable gases are divided into minute globules and are thoroughly disseminated in the condensing water. The current of water is so rapid that these air cells have no opportunity to combine and form large bubbles, and thus escape upwardly in the condenser. It is this multiple and cumulative function of the condensing water that renders the apparatus so efficient, enabling gases to be readily and effectively removed from closed vessels.

Located centrally within the shell of the condenser is a vertically - disposed pipe 7 which opens into the casing through the bottom casting thereof. The water for effecting condensation is supplied through this pipe. On its upper open end is fitted a cone-like cap 8 which forms a deflector, and immediately beneath this cap the pipe is formed with a series of perforations 9. Beneath the perforations 9 is a collecting funnel 10 which at its upper, outer edge is secured to the shell of the condenser, the bottom of such funnel being inclined toward the water pipe. Immediately beneath the lower contracted opening of the collecting funnel is a deflector 12, in the form of an inverted funnel secured at its upper inner end directly to the pipe, and then beneath this deflecting funnel is a second series of openings 13. This construction is maintained throughout the length of the condenser, that is, beneath each deflector is a series of water outlet openings, and beneath the latter is a collecting funnel for concentrating the discharge of the water and vapors onto the next lower distributing funnel. Each set of distributing and collecting funnels and series of spray holes constitute a unit. As many of these units may be used

in a condenser as are required to thoroughly condense or liquefy the vapors and to dissolve the non-condensable gases.

The operation of the condenser is as follows:—The water supplied to the vertical pipe 7 will be ejected in sprays through the several series of outlets. The vapor to be liquefied or condensed enters the condenser through the top head, and encounters the first spray of cooling water directly below the top deflector 8. Some of the vapor is immediately condensed, but that which escapes contact with the water is forced downward and must pass through this water which now flows in a thin sheet from the upper collecting funnel to the inverted deflecting funnel below. This is continued throughout the length of the condenser, the action of which is not only multiple but cumulative, since the thickness of the sheet of water running down the several funnels increases with each unit. The condensed vapors and the cooling water will accumulate at the bottom of the condenser, and within the outlet pipe 5. The weight of this column of water is equal to atmospheric pressure. The action thereof effects the withdrawal of the gases from the impregnating apparatus or other closed vessel, without requiring the use of a pump, the standing column of water acting as a barometric tube. The normal height of the column of water is indicated in Fig. 1.

It is to be noted that the gases are not condensed instantaneously, but the operation is gradual or progressive, not being completed until they reach the last or lowermost spraying and intermingling unit. As the water passes upward through the supply pipe it is gradually heated by the gases, with the result that the work accomplished by the upper or topmost unit can in no instance be complete, and each successive unit has its own work to perform. By reason of this gradual accomplishment of the work, a much higher velocity is obtained for the cooling water, and the size of the non-condensable globules of gas is gradually reduced, further reduction being effected by each unit, and on account of the increasing velocity and volume of water these globules have no opportunity to escape upwardly, and as they reach

the last or lowermost unit their combined volume is greatly reduced by the gradual cooling to which they have been subjected, the water at the last or lowermost unit being cooler than that at any of the points above.

The advantages of our invention will be apparent to those skilled in the art. By employing a number of separate units the efficiency of the condenser is augmented to such a degree as to enable the cooling water to divide non-condensable gases, such as air, into minute globules and remove them from the chamber by means of the rapid current. This is due to the thorough and repeated intermingling of the gases and cooling water in passing through each unit.

We claim as our invention:

A vacuum producing apparatus comprising a casing having an inlet for the gases at its upper end, a vertically-disposed water pipe located within said casing and having separate series of outlets, a series of collecting funnels extending inwardly from the casing toward the water pipe, and a series of deflectors extending from the pipe outwardly toward the casing, the funnels being located each beneath a series of outlets, and the deflectors located each beneath the lower open end of a funnel, water being supplied to said pipe at its lower end, so that the temperature of the water will effect a gradual decrease in the temperature of the gases as the latter travel downwardly, the gases in passing downwardly being intermingled with the water and subjected to the successive action of sprays of water of gradually reduced temperature.

In testimony whereof, we have signed this specification in the presence of two subscribing witnesses.
